TOOL DRESSING APPARATUS

Filed Feb. 27, 1928

UNITED STATES PATENT OFFICE

CLARENCE G. WARREN, OF KELLYVILLE, OKLAHOMA, ASSIGNOR TO GEORGE KRELL,
OF SAPULPA, OKLAHOMA

TOOL-DRESSING APPARATUS

Application filed February 27, 1928. Serial No. 257,206.

My invention relates to apparatus for dressing oil well drilling tools and more particularly to a ram line adjuster for such apparatus, the invention having for its principal object to expedite the positioning of the tool dressing ram in proper functional position relative to the drill bits to be "dressed."

In accomplishing this and other objects of the invention I have provided improved details of structure, the preferred forms of which are illustrated in the accompanying drawings, wherein:

Fig. 1 is a perspective view of a portion of a derrick illustrating use of my invention.

Fig. 2 is a detail perspective view of the ram connector bar, and

Fig. 3 is a detail perspective view of the ram connector link.

Referring more in detail to the drawings: Fig. 1 designates an oil well drilling rig including a derrick platform 2, band wheel 3, band wheel shaft 4, and the crank 5 which ordinarily operates the walking beam 6 through the pitman 7, as in common oil well practice.

Mounted on the derrick platform 2 in line with the crank 5 is a block support 8 and an anvil 9, so positioned as to support a drill bit 10 with the pin 11 thereof resting in a socket 12 of the block and the body portion resting upon the anvil so that its cutting end is facing the crank, as clearly shown in Fig. 1, in position to be "dressed" by a swinging ram 13 suspended from the top of the derrick and operated by the band wheel crank 5, as now described.

Suspended from the crank block (not shown) of the derrick in alignment with the crank 5 and the bit 10 is a cable 14 for supporting a connector bar 15 by a coupling link 16 comprising a rectangular body portion 17 having hooks 18 at its upper and lower ends, the upper hook engaging a loop 19 formed on the end of the cable 14, and a slot 20 in the body portion 17 of slightly greater depth than the width of the bar for receiving the bar and supporting it in a substantially horizontal position, as presently described.

The bar 15 comprises a flat body portion 20 having a plurality of notches 21 and 22

formed in its upper and lower edges respectively, and an integral neck portion 23 having a threaded end 24 directed toward the crank 5 to which it is coupled by a connecting rod 25 having a threaded socket 26 mounted on the threaded neck of the bar and an eye 27 at its opposite end attached to the crank by a bolt 28 which extends through the eye and through one of the wrist pin openings 29 of the crank, so that the rotation of the crank effects reciprocation of the bar 15 in the longitudinal direction of the bit to actuate the ram suspended therefrom as now described.

30 designates a link similar to the link 16, having a slot 31 receiving the connector bar 15 with the upper edge of the slot seating in one of the notches 21 in the bar. The link 30 is further provided with hooks 32, the depending hook suspending a chain 33 which is connected at its lower end with a loop 35 on the ram, the chain being of a length to position the ram in end alignment with the bit. In order to prevent curving or flexing of the chain 33 when the ram is in operation, a pipe 36 is preferably sleeved over the chain as shown in Fig. 1.

In dressing a bit with the apparatus above described, the bit is positioned on the derrick floor with its pin resting in the block 8 and its cutting end on the anvil pointing in the direction of the ram. With the parts so arranged, the pitman 7 is disconnected from the crank 5, the connecting rod 25 attached to the crank 5 by inserting the bolt 28 in an opening of the crank to give the proper swing to the ram and the connector link 16 engaged in one of the notches 22 in the lower edge of the bar, so that the bar is supported in a substantially horizontal position when the crank is on dead center. The ram is then suspended from the bar by engaging the slot of the connector link 30 with one of the notches 21 in the top edge of the bar so that the ram is positioned in front of the bit to give the proper blow which may be varied by moving the link 30 into any one of the notches 21.

The band wheel is then rotated to cause the crank to reciprocate the bar and swing the ram into contact with the bit, the ram

being guided by the driller or tool dresser to direct the force of the blow against the desired place on the bit.

It is apparent that with my apparatus a ram line may be readily adjusted to vary the force of the blow and position the ram with relation to the length of the bit to be "dressed".

What I claim and desire to secure by Letters Patent is:

- 10 1. Tool dressing apparatus including a ram line, a bar supported by the line, a ram suspended from the bar, means for actuating the bar to operate the ram, and means for adjusting the ram transversely of the line.
- 15 2. Tool dressing apparatus including, in combination with a crank, a suspended ram line, an actuating bar supported by the line, driving connection between the bar and the crank, a ram suspended from the bar, and means for adjusting the ram longitudinally of the bar.
- 20 3. Tool dressing apparatus including a ram line, a bar supported by the ram line and having a plurality of notches on its upper edge, an actuating crank, driving connection between the crank and the bar, a ram, a hook member engaging one of the notches in the bar, and connection between the hook member and the ram for supporting the ram.
- 25 4. Tool dressing apparatus including a ram line, a bar supported by the line, an actuating crank, a connector between the crank and the bar, a hook member supported by and adjustable longitudinally of the bar, and a ram suspended from the hook member.
- 30 5. Tool dressing apparatus including a ram line, a bar suspended from the line, means for reciprocating the bar, a hook member supported by and adjustable longitudinally of the bar, and a ram suspended from the hook member.
- 35 6. Tool dressing apparatus including a ram line, a horizontal bar suspended from the line, means for reciprocating the bar, a ram, and means longitudinally adjustable on the bar and supporting the ram longitudinally of the bar.
- 40 7. Tool dressing apparatus including a ram-supporting member, a reciprocator therefor, a ram line adjustably supporting the ram-supporting member, and a ram adjustably suspended from the ram-supporting member.
- 45 8. Tool dressing apparatus including a ram line, a bar supported by the line, an actuating crank, a connector between the crank and the bar, a hook member having a slot receivable by the bar, the hook member being supported by and adjustable longitudinally of the bar, and a ram suspended from the hook member.
- 50 9. Tool dressing apparatus including a ram line, a bar having notches in its upper and lower edges, a pair of hook members having slots receivable by the bar and hook

portions on their ends, the bar supported from the line by one hook member engaging one of the lower notches in the bar, an actuating crank, a connector between the crank and the bar, and a ram suspended from the other hook member engaging one of the upper notches in the bar.

10. Tool dressing apparatus including a ram line, a bar having notches in its upper and lower edges in staggered relation, a pair of hook members having slots receivable by the bar and hook portions on their ends, the bar supported from the line by one hook member engaging one of the lower notches in the bar, an actuating crank, a connector between the crank and the bar, and a ram suspended from the other hook member engaging one of the upper notches in the bar.

In testimony whereof I affix my signature.

CLARENCE G. WARREN.
